OTHER PUBLICATIONS

Ray Padula (Brand Name) Product No. RP-SRSP, shown in Attachment 1, was apparently sold or offered for sale at least by May of 2008.

(Continued)

Primary Examiner — Robin V Webster(74) *Attorney, Agent, or Firm* — Austin Rapp(57) **CLAIM**

The ornamental design for a hose nozzle, as shown and described.

DESCRIPTION

FIG. 1 is a first top perspective view of a hose nozzle, according to my new design;
FIG. 2 is a second top perspective view of the hose nozzle;
FIG. 3 is a first bottom perspective view of the hose nozzle;
FIG. 4 is a second bottom perspective view of the hose nozzle;

FIG. 5 is a front side elevational view of the hose nozzle;
FIG. 6 is a rear side elevational view of the hose nozzle;
FIG. 7 is a top side view of the hose nozzle;
FIG. 8 is a bottom side view of the hose nozzle;
FIG. 9 is a left side elevational view of the hose nozzle;
FIG. 10 is a right side elevational view of the hose nozzle;
and,
FIG. 11 is a right side elevational view of the hose nozzle in an alternative position.

The broken lines in the figures illustrate boundaries between claimed and unclaimed regions of the hose nozzle and form no part of the claimed design.

1 Claim, 11 Drawing Sheets(56)
